Primary Examiner — Jeffrey D Asch*Assistant Examiner* — Caitlin A Laverty(74) *Attorney, Agent, or Firm* — Suzanne Kikel, Patent Agent(57) **CLAIM**

The ornamental design for a car umbrella holder, as shown and described.

DESCRIPTION

FIG. 1 is a front perspective view of a car umbrella holder mounted on a car door, showing my new design.

FIG. 2 is a front perspective view of the car umbrella holder of FIG. 1.

FIG. 3 is a front elevational view of the car umbrella holder of FIG. 2.

FIG. 4 is a rear elevational view thereof.

FIG. 5 is a left side view thereof.

FIG. 6 is a right-side view thereof.

FIG. 7 is a top plan view thereof; and,

FIG. 8 is a bottom plan view thereof.

The broken lines in FIG. 1 representing the inside of a car door and an umbrella form no part of the claimed design.

1 Claim, 7 Drawing Sheets(56)
